PAPER TOWEL AND WAX PAPER DISPENSER

Manuel S. Ziskin, Mayfield Heights, and Ralph B. Billig, Willoughby, Ohio, assignors to Kromex Corporation, Cleveland, Ohio, a corporation of Ohio

Application March 13, 1952, Serial No. 18,862

Term of patent 14 years

(Cl. D4—3)

To all whom it may concern:

Be it known that we, Manuel S. Ziskin and Ralph B. Billig respectively, citizens of the United States of America, residing respectively at Mayfield Heights, county of Cuyahoga, and State of Ohio, and Willoughby, county of Lake, and State of Ohio, have invented a new, original, and ornamental Design for Paper Towel and Wax Paper Dispenser, of which the following is a specification, reference being had to the accompanying drawing, forming a part hereof.

Fig. 1 is a top plan view of a paper towel and wax paper dispenser, showing our new design;

Fig. 2 is a front elevational view thereof;

Fig. 3 is a side or end elevational view thereof, as viewed from the left side of Fig. 2, with portions broken away to show the cross-sectional contour of the front of the dispenser, and

Fig. 4 is a rear elevational view thereof.

The dominant features of our design reside in those portions shown in full lines.

We claim:

The ornamental design for a paper towel and wax paper dispenser, substantially as shown and described.

MANUEL S. ZISKIN
RALPH B. BILLIG.
